(57) **CLAIM**

The ornamental design for a design for condiment container as shown and described.

DESCRIPTION

FIG. 1 is an upper perspective view of a condiment container.

FIG. 2 is a lower perspective view thereof.

FIG. 3 is a front view thereof.

FIG. 4 is a rear view thereof.

FIG. 5 is a first side thereof.

FIG. 6 is a second side view thereof.

FIG. 7 is a top view thereof; and,

FIG. 8 is a bottom view thereof.

The broken lines shown in the drawings depict portions of the condiment container that form no part of the claimed design.

1 Claim, 8 Drawing Sheets
